BOILER FEED TRAP

Filed Oct. 15. 1926

INVENTOR
S. L. TILL,
BY
W. E. Beck, Jr.
ATTORNEY

UNITED STATES PATENT OFFICE.

STEVEN L. TILL, OF CHICAGO, ILLINOIS.

BOILER FEED TRAP.

Application filed October 15, 1926. Serial No. 141,795.

My invention relates to feed traps for boilers and has for its object to provide means for automatically supplying water to the boiler.

5 A further object is to provide a device of this character which is noiseless in its operation, simple in construction and reliable in performance.

10 Other objects and advantages will become apparent from the following detailed description when viewed together with the accompanying drawing forming part hereof wherein like numerals refer to like parts throughout the specification and in which

15 Figure 1 is a vertical sectional view through the trap,

Figure 2 is a similar view in cross section, and

20 Figure 3 is a section taken along a line 3—3 of Figure 2.

Referring now to the drawing I have disclosed my invention as comprising a housing

5 having a head 6 and through which is transversely arranged a tubular shaft 7.

25 The shaft has one end rotatably mounted in a removable plate 8 secured to one side of the housing, the plate being provided with a plug 9. The opposite end of the shaft is rotatably carried in a substantially similar plate 10 removably secured to the opposite side of the housing and also provided with a plug 11.

30 A sleeve 12 is arranged on the end of the shaft extending within the plate 10 and is fixedly secured in the plate, the shaft being freely rotatable within the sleeve. The plate is provided with a pair of openings preferably arranged at right angles with respect to each other, one opening 13 extending upwardly from the center of the plate and has an exhaust pipe 14 connected thereto. The other opening 15 extends from the center of the plate toward one side thereof and has a steam feed pipe 16 connected thereto. The

45 sleeve 12 is provided with a pair of passages 17, one of which communicates with the opening 13 and the other of which communicates with the opening 15 and the shaft is provided with a passage 18 selectively communicable with either of the passages 17. The shaft being rotatable, it is obvious that the passage 18 is adapted to register either with the steam pipe 16 or the exhaust pipe 14.

Intermediate the ends of the shaft is provided an opening 19 communicating with a small chamber 20 formed within a bushing 21 fixedly secured to the shaft within the housing. Shoulders 22 are formed on opposite sides of the bushing to one of which is secured a vacuum cup 23 opening downwardly and above which is arranged a bowl 24 opening upwardly, and to the opposite shoulder is secured a counter-weight float 25. Extending upwardly from the bushing and communicating with the chamber 20 is an overflow pipe 26 having its outlet within the housing.

55 A feed pipe 27 is connected to the base of the housing terminating in a coupling 28 through one side of which extends a water feed pipe 29 having interposed therein a check valve 30 and through the opposite side of which extends a steam pipe 31 leading to the boiler and having interposed therein a check valve 32.

60 A trigger mechanism is arranged within the housing immediately beneath the counter-weight float 25 and comprises a small float 33 pivotally mounted upon a support 34 carried upon a removable plate 35 secured to the base of the housing. A suitable gauge 36 may be arranged at one side of the housing.

65 In the operation of the device when the trap or housing is filled with water the device will occupy a position substantially similar to that shown by the full lines in Figure 1. Steam therefore is permitted to enter the tubular shaft 7 from the pipe 16 through the passageways 17 and 18 and will enter the housing through the opening 19 and the overflow pipe 26. Such action will force the water out through the pipe 27 past the check valve 32 and into the boiler through the pipe 31. As the water is 70 emptied from the trap the vacuum cup 23 is pulled downwardly and the counter-weight float 25 will be raised slightly upwardly thereby releasing the trigger 33 and moving the various parts into the position shown by the dotted lines in Figure 1. Such action rotates the shaft 7 closing the steam intake and allowing the water to enter by way of the supply pipes 29 and 27 filling the trap and allowing the steam therein to escape out 75 through the shaft 7 by way of the exhaust pipe 10. The steam pipe 31 is connected to the

14. As soon as sufficient water has again entered the trap the parts will be returned to the position as shown in the full lines in Figure 1 so as to continue the automatic feed of the water as described above.

5 I claim:

1. A feed trap comprising a housing, a tubular shaft rotatably arranged therein, steam feed and exhaust pipes communicating with said shaft, a water pipe entering the housing and means within the housing for rotating the shaft to selectively register with either the steam feed or exhaust pipe.

10 2. A feed trap for boilers comprising a housing, a tubular shaft arranged therein, steam feed and exhaust pipes connected thereto, a water feed pipe entering the housing and a float secured to the shaft and arranged to rotate the same so as to successively register the shaft with said feed and exhaust pipes.

15 3. A feed trap comprising a housing, a tubular shaft rotatably mounted therein, a sleeve at one end of the shaft, passages through the sleeve and the shaft, a steam feed pipe and a steam exhaust pipe communicating with the passages in said sleeve, a water pipe entering the housing, and a float carried by the shaft and adapted to rotate the same so as to selectively register the passage in the shaft with the passages in said sleeve.

20 4. A feed trap comprising a housing, a tubular shaft rotatably mounted therein, a sleeve at one end of the shaft, passages in said shaft and said sleeve, a steam feed pipe and a steam exhaust pipe communicating with the passages in said sleeve, a water feed pipe entering the housing, a bushing formed on the shaft within the housing and having an opening extending to within the shaft, shoulders formed at opposite sides of the bushing, a vacuum cup formed on one of said shoulders, a float formed on the other of said shoulders and a trigger-float operatively engaging said first named float.

25 5. A feed trap comprising a housing, a tubular shaft rotatably carried therein, a sleeve at one end of the shaft, passages in the sleeve and the shaft, a steam feed pipe communicating with one of said sleeve passages, a steam exhaust pipe communicating with another of said sleeve passages, a bushing formed on the shaft within the housing and having an opening communicating to within the shaft, shoulders formed on said bushing, a vacuum cup having a bowl thereabove attached to one of said shoulders, a float attached to the other of said shoulders, a trigger-float pivotally mounted within the housing and adapted to engage said first named float, a water feed pipe communicating with the housing and with the boiler and means interposed in said pipe to control the flow of water therethrough.

6. A feed trap comprising a rotatably mounted hollow shaft interposed in a feed line and having an opening therein, intake and exhaust pipes communicable with said opening and means carried on the shaft 70 adapted to move the opening into or out of communication with either of said pipes.

7. A feed trap comprising a rotatably mounted hollow shaft interposed in a feed line and having an opening therein, intake 75 and exhaust pipes communicable with said opening, means carried on the shaft adapted to move the opening into or out of communication with either of said pipes and means affording access from the feed line through 80 the shaft.

8. A feed trap comprising a rotatably mounted hollow shaft interposed in a feed line and having an opening therein, intake 85 and exhaust pipes communicable with said opening, means carried on the shaft adapted to move the opening into or out of communication with either of said pipes and a trap chamber having communication with said shaft and the feed line.

9. In combination with a boiler feed line of a feed trap interposed therein comprising a rotatably mounted shaft having an opening, intake and exhaust pipes communicable therewith, means carried on the shaft for moving said opening into or out of communication with either of said pipes and a trap 95 chamber interposed between the shaft and the feed line and communicable with either thereof.

10. In combination with a boiler feed line of a feed trap interposed therein comprising a rotatably mounted shaft having a plurality of openings, intake and exhaust pipes communicable with one of said openings, means carried on the shaft for moving said opening into or out of communication with either of said pipes and a trap chamber communicating with the feed line and the other of said openings.

11. In combination with a boiler feed line of a feed trap comprising a trap chamber interposed therein, a hollow shaft rotatably mounted in said chamber and having openings communicating within and without the chamber, intake and exhaust pipes communicable with said opening without the chamber, a float mounted on the shaft within the chamber and means releasably engaging the float adapted to temporarily restrain movement of the shaft.

12. In combination with a boiler feed line of a feed trap comprising a trap chamber interposed therein, a hollow shaft rotatably mounted in said chamber and having openings communicating within and without the chamber, intake and exhaust pipes communicable with said opening without the chamber, a float mounted on the shaft within the chamber, means releasably engaging the float 125 130

whereby to restrain movement of the shaft and means connected with the float adapted to release said restraining means.

13. In combination with a boiler feed line of a feed trap comprising a trap chamber interposed therein, a hollow shaft rotatably mounted in said chamber and having openings communicating within and without the chamber, intake and exhaust pipes commu-

nicable with said opening without the chamber, a float mounted on the shaft within the chamber, means releasably engaging the float whereby to restrain movement of the shaft and a suction cup connected with the float adapted to release said restraining means. 15

In testimony whereof I affix my signature.

STEVEN L. TILL.
